UNITED STATES PATENT OFFICE

EDWARD A. FARR, OF MERIDEN, CONNECTICUT, ASSIGNEE TO MANNING, BOWMAN & CO., OF MERIDEN, CONNECTICUT, A CORPORATION OF CONNECTICUT

DESIGN FOR A CLOCK CASING

Application filed December 13, 1930. Serial No. 37,987. Term of patent 7 years.

To all whom it may concern:

Be it known that I, EDWARD A. FARR, a citizen of the United States, residing at Meriden, in the county of New Haven, State of Connecticut, have invented a new, original, and ornamental Design for a Clock Casing, of which the following is a specification, reference being had to the accompanying drawing, forming a part thereof.

The figure is a perspective view of a clock casing showing my new design.

I claim:

The ornamental design for a clock casing as shown.

EDWARD A. FARR.
